(57) **CLAIM**

The ornamental design for a shoulder portion of an automobile tire, as shown and described.

DESCRIPTION

FIG. 1 is a perspective view of a shoulder portion of an automobile tire according to our new design;

FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a bottom view thereof;

FIG. 8 is a fragmentary enlarged front view thereof;

FIG. 9 is a cross-sectional view taken along line 9-9 in FIG. 8 thereof; and,

FIG. 10 is a fragmentary enlarged view of the shoulder portion of an automobile tire of FIG. 5.
